CLAIM

The ornamental design for a lighting sconce with elbow, as shown and described.

DESCRIPTION

FIG. 1 is a left front upper perspective view of a lighting sconce with elbow showing our new design.

FIG. 2 is a left front perspective exploded view of a lighting sconce with elbow showing our new design.

FIG. 3 is a right rear lower perspective exploded view of a lighting sconce with elbow showing our new design.

FIG. 4 is a right rear perspective view of a lighting sconce with elbow showing our new design.

FIG. 5 is a left elevational view of a lighting sconce with elbow showing our new design.

FIG. 6 is a front elevational view of a lighting sconce with elbow showing our new design.

FIG. 7 is a right elevational view of a lighting sconce with elbow showing our new design.

FIG. 8 is a back elevational view of a lighting sconce with elbow showing our new design.

FIG. 9 is a top plan view of a lighting sconce with elbow showing our new design; and,

FIG. 10 is a bottom plan view of a lighting sconce with elbow showing our new design.

The broken lines shown on the drawings depict portions of the lighting sconce with elbow that form no part of the claimed design.
